TEXTILE FABRIC OR SIMILAR ARTICLE

Sergei Bogdanovich, Carmel, N. Y., assignor to Weil & Durrse, Inc., New York, N. Y., a corporation of New York

Application April 4, 1956, Serial No. 40,910

Term of patent 7 years

(Cl. D92—1)

The figure is a face view of a textile fabric or similar article, showing my new design. The full width of the fabric is disclosed vertically and the design repeats along the length of the fabric as indicated horizontally on the drawing.

I claim:

The ornamental design for a textile fabric or similar article, as shown and described.
